[57] ABSTRACT

A skidder tractor includes a vertically swingable stacking blade assembly at its forward end, the assembly comprising a pair of push arms located at the opposite sides of the tractor front end and having their forward ends joined by a blade. A stacking blade extension assembly is fixed to the stacking blade assembly for preventing elongate objects such as logs or rocks or the like from passing over the blade into a position whereat they would be disposed between the blade assembly and the underside of the tractor.

4 Claims, 2 Drawing Figures

PATENTED JAN 22 1974

3,786,872

FIG. 1

FIG. 2

EXTENSION ASSEMBLY FOR A SKIDDER TRACTOR STACKING BLADE ASSEMBLY

BACKGROUND OF THE INVENTION

This invention relates to a tractor-mounted blade in which the blade is carried on a pair of vertically movable arms extending forwardly at the opposite sides of the tractor. More particularly, this invention relates to improvements in the stacking blade extension assembly disclosed in U. S. Pat. No. 3,543,867 issued on 1 Dec. 1970 to Smemo et al.

In the Smemo et al. patent, a skidder-type tractor is provided with a stacking blade which has an extension assembly integral therewith for preventing large items being engaged by the blade from rolling over the blade and finding their way to the space between the blade push arms and the front and bottom of the tractor front end.

The extension assembly of the Smemo et al device does not work entirely satisfactorily since when the skidder tractor is being used in a log decking operation, for example, it sometimes becomes desirable to even the ends of a bunch of logs in a pile and when attempting this operation with the Smemo et al device, logs sometimes move endwise above the blade into the space between the blade and the front of the tractor.

SUMMARY OF THE INVENTION

It is therefore the primary object of the present invention to provide an extension assembly for a stacking blade, which assembly acts to prevent logs, or the like, from passing either endwise or lengthwise across the top of the main blade into the area located above the push arms of the blade and the bottom and front of the tractor. A more specific object of the invention is to provide such an extension assembly which not only serves the function aforementioned but also serves to reinforce the stacking blade and the push arms.

BRIEF DESCRIPTION OF THE DRAWING

FIG. 1 is a side view of the front portion of a skidder tractor with portions being broken away, and showing a blade provided with an extension assembly constructed according to the principles of the present invention.

FIG. 2 is a front perspective view of a portion of the stacking blade and extension assembly shown in FIG. 1.

DESCRIPTION OF THE PREFERRED EMBODIMENT

It is here noted that at times in the following discussion reference will be made to pairs of members while in some instances only one of the members is disclosed in the drawing. When such instances occur, it can be assumed that the missing member is identical to the one being described and that it is used in an identical manner.

Referring then to FIG. 1, therein is shown a vehicle front end portion 10 such as the front end portion of a skidder tractor of the like. The vehicle front end portion 10 includes a main fore-and-aft extending frame 12 which is supported on a pair of front ground wheels 14. The main frame 12 includes opposite side portions 16 which extend fore and aft at the opposite sides of the vehicle and are joined at their forward ends to a grille

housing 18, the bottoms of the sides 16 and the grille housing 18 terminating at a generally planar underside 20 of the vehicle and the forward end of the grille housing 18 terminating at a generally planar front end 22 of the vehicle, the bottom side and front end forming an angle of approximately 90° with one another. Located behind the grille housing 18 and bounded at its lower portion by the opposite frame side portions 16 is an engine compartment 24 having a hood 26 extending thereover.

Fixed to the opposite sides of the main frame 12 are a pair of mounting brackets 28. A pair of fore-and-aft extending push arms means 30 include main members 32 respectively connected to the pair of brackets 28 by means of horizontal pivot pins 34 providing a pivot about which the push arms means 30 are vertically pivotable. For the purpose of selectively vertically pivoting the push arms, there is provided a pair of horizontally disposed hydraulic actuators 36 which are fixed to the brackets 28 and have their respective rods pivotally connected as at 38 to the rearward ends of a pair of upwardly and rearwardly inclined members 40 forming a part of the push arm means and respectively having their forward ends fixed rigidly with the top of the push arm main members 32. Extending between the main members 32 and the portions 40 are a pair of bracing members 42. The forward ends of the push arms means 30 terminate forwardly of the forward end 22 of the vehicle and are secured to the rear side 44 of a transversely extending stacking blade 46 having a forwardly facing material-engaging surface 48 which is connected to the backside 44 through means of transversely extending top and bottom surfaces 50 and 52, respectively.

For the purpose of preventing objects such as large stones, logs or the like from moving over the top surface 50 of the blade 46 into a space 54 which, as viewed from the side of the vehicle when the blade is in a lowered working position as shown in FIG. 1, is defined by the bottom 20 of the vehicle forward end portion and the top of the push arms means 30, there is provided a blade extension assembly 56. The extension assembly 56 includes a pair of upright posts respectively having their lower ends fixed as by weldments to the push arm members 32 adjacent the backside 44 of the blade 46, the forward side portion of the posts being also fixed as by weldments to the backside 44 and top surface 50 of the blade 46. Thus, it can be appreciated that the posts 58 reinforce the top portion of the blade 46. The posts 58 include forwardly facing surfaces 60 which extend generally tangentially to and form upward continuations of the curved material-engaging surface 48 of the blade. The posts 58 include upper rearwardly extending portions 62 which, when the blade is in its lowered position shown in FIG. 1, extend upwardly and rearwardly to a point adjacent the bottom of the front end of the vehicle. Respectively connected to the rearward ends of the portions 62 is one of the ends of a pair of rearwardly extending members 64, the other ends of the members 64 being respectively secured to the upwardly and rearwardly inclined members 40. A cross member 66 extends between and is secured to the upright posts 58 and includes a bottom edge means which is secured to the top surface 50 of the blade 46. The cross member 66 includes a front surface 68 which cooperates with the surfaces 60 of the upright posts 58 in forming an upward extension of the blade surface 48.

Thus, it can be easily perceived from reviewing FIG. 1 that the cross member 66 substantially reduces the vertical clearance α which would otherwise exist between the top surface of the blade 46 and the bottom of the front end of the vehicle, hence, reducing the possibility that an elongate object might move endwise into the space 54 when the blade 46 is being used to move such elongate objects. It is also apparent that the cross member 66 increases the transverse rigidity of the posts 58. Further, as can best be seen in FIG. 1, the cross member 66 does not limit the upward swinging movement of the blade 46, since, when the blade 46 is in its uppermost position, the cross member 66 extends parallel to the forward end of the vehicle. It is also here noted that when the blade 46 is in its lowered position resting on the ground as shown in solid lines in FIG. 1, the rearwardly extending members 64 are substantially at the same level as and are generally parallel to the bottom of the vehicle.

It is thought that the operation of the blade extension assembly 56 is apparent from the foregoing description and for the sake of brevity no further description of the operation is given. Suffice it to say that the extension assembly 56 is compact and rigid and rigidifies the blade and push arm structures, all in addition to performing the function of keeping material from passing over the blade 46 into the space 54 when the blade is in the lowered working positions.

We claim:

1. A vehicle and stacking blade assembly combination comprising: said vehicle having a fore-and-aft extending forward end portion including a main frame having portions at the opposite sides of the vehicle; said stacking blade assembly including a pair of push arm means having their respective rear ends pivotally secured to the main frame at opposite sides of the vehicle by means permitting vertical swinging movement of the arm means, the forward ends of the arm means extending beyond the front end of the vehicle; a pair of reciprocable hydraulic actuators being respectively connected between the main frame and rear end portions of the arm means for swinging the arms vertically; a blade being fixed to the forward ends of said arm means and having an upper transverse edge which, when the blade is in a lowered position resting on the ground, is located at a level below the level of the bottom of the front of the vehicle; said blade further including a forwardly facing material-engaging surface; an extension assembly including a pair of upright posts having their bottom ends respectively rigidly fixed to the upper

5 sides of the push arm means adjacent said blade and having a forward surface forming an upward continuation of the material-engaging surface of the blade, said posts having upper rearwardly extending portions inclined rearwardly and upwardly from said forward surface to a location adjacent the bottom of the front end of the vehicle when the blade is in said lowered portion; a pair of rearwardly extending members respectively located at opposite sides of the vehicle and each having 10 forward and rearward ends respectively fixed to one of the rearwardly extending post portions and to one of the push arm means, the rearwardly extending members each being generally parallel to and at the same level as the bottom of the forward end portion of the vehicle when the blade is in said lowered position; and a cross member extending between and having opposite ends fixed to the posts and having a lower edge means fixed to the top of said blade; and said cross member further including a forward surface forming an 15 upward continuation of the material-engaging surface of the blade.

2. The combination as defined in claim 1 wherein the upright posts include portions secured to the back and top sides of the blade.

25 3. The combination as defined in claim 1 wherein the push arm means each include a main fore-and-aft member and an upwardly and rearwardly inclined member having one end secured to the top of the main member, at a location spaced forwardly from the connection of the push arm means with the vehicle main frame, and having its other end pivotally connected to one end of one of said pair of reciprocable hydraulic actuators; and said rearwardly extending members of said extension assembly respectively having their rearward ends 30 respectively connected to said upwardly and rearwardly inclined members.

40 4. The combination as defined in claim 2 wherein the push arm means each include a main fore-and-aft member and an upwardly and rearwardly inclined member having one end secured to the top of the main member, at a location spaced forwardly from the connection of the push arm means with the vehicle main frame, and having its other end pivotally connected to one end of one of said pair of reciprocable hydraulic actuators; and said rearwardly extending members of said extension assembly respectively having their rearward ends 45 respectively connected to said upwardly and rearwardly inclined members.
